UNITED STATES PATENT OFFICE.

GUIDO BORGHESANI AND GIUSEPPE STAMPA, OF ROME, ITALY.

PREPARATION OF NEW FERTILIZER.

1,272,001.

Specification of Letters Patent.

Patented July 9, 1918.

No Drawing.

Application filed April 7, 1917. Serial No. 160,559.

To all whom it may concern:

Be it known that we, GUIDO BORGHESANI and GIUSEPPE STAMPA, subjects of the King of Italy, and both residing at Rome, Italy, 5 have invented certain new and useful Improvements in Preparation of a New Fertilizer, of which the following is a specification.

The aim of this invention is to prepare a 10 new fertilizer with a basic reaction and containing phosphoric anhydrid and potash, almost entirely soluble, at ordinary temperature in citric acid (an aqueous solution of 2% of citric acid).

15 The method consists in reducing to fragments or powder:—

(a) Rocks and minerals containing potassium silicate (for example leucite).

20 (b) Rocks and minerals containing calcium phosphates (for example phosphorites).

(c) Sodium bisulfate (niter-cake) residue of the manufacture of nitric acid from sodium nitrate.

25 (d) Ashes of pyrites— and in placing in a suitable furnace (for example an electric furnace) with a temperature sufficiently high to reduce to a flux a mixture of the said substances, in which the sodium bisulfite and the ashes of pyrites (which constitute the reagent for dissolving the potassium and phosphorus) represent only a relatively small percentage (for example $\frac{5}{10}$ % in all) of the total mass subject 30 to reaction.

The sodium bisulfate may be entirely or partly substituted by other salts, having however, the quality of developing either strong mineral acids; or elements which are 40 very active when subjected to a high temperature.

45 Experience has shown that a similar result may be obtained, that is, the solubility of potassium and phosphorus, by moistening uniformly the mixture of phosphoric and potassic minerals with a relatively small proportion of mineral acids, and by putting this mixture, so moistened, first into a closed vessel with a temperature of about 600° C. 50 and afterward into a reacting furnace sub-

jected to a temperature sufficiently high to bring it to a fluid state.

By operating with a closed vessel, and better still by means of pressure and humidity, before transferring the mixture to the reacting furnace (electric), positive results of solubility are also obtained by heating in the presence of carbonic acid, chlorin and fluorin.

Thus the addition of pyritic ashes is not 60 always necessary, and these ashes may be substituted for example by slags containing manganese (residue of the manufacture of manganese steel).

It has been found, in fact, that even the 65 most simple mixture of phosphoric and potassic minerals (especially if the potassic mineral leucite of the volcanic beds of the Latium or of the Campania be used), without any of the above-mentioned additions, 70 produces a flux in which the greater part of the potassium (and even of the phosphorus), is rendered soluble. To obtain this result it will suffice that the separation of the leucite from the gangue which naturally accom- 75 panies it, be not brought to the extreme degree of perfection, for it seems that the small percentage of gangue which is found with the leucite, acts as a catalyst. Certain phosphorites, on account perhaps of the 80 high percentage of iron contained in them, lend themselves easily to the manufacture of the new fertilizer, without the addition of substances which cause the above-mentioned action of solubility.

85 The heating of the reacting mass in the furnace is brought to a temperature of about 1200°–1400° C. and the substance is kept at this temperature till a flux is formed.

The flux thus obtained (and it is the 90 formation of an even flux which determines the temperature that is most convenient to the reaction), is then removed from the furnace and left to cool in the air. It may also be cooled rapidly by sprinkling with water 95 in sufficient quantity for its own evaporation, so as to procure a substance absolutely dry. Afterward it is submitted to mechanical molding.

The powder thus formed by the molding 100

constitutes a basic phosphoro-potassic manure soluble in citric acid of 2%.

What we claim is:—

In the preparation of fertilizer, a process
5 which consists in mixing phosphoric mineral, potassic mineral and sodium bisulfate, subjecting the mixture to a temperature sufficient to fuse the mass, cooling the fused material, and reducing the same to the form
10 of powder containing phosphoric acid and potash soluble in 2% citric acid.

In witness whereof we have hereunto signed our names in the presence of two witnesses.

DR. GUIDO BORGHESANI.
DR. GIUSEPPE STAMPA.
